UNITED STATES PATENT OFFICE

HERBERT R. BLISS, OF NIAGARA FALLS, NEW YORK, ASSIGNOR TO H. R. BLISS COMPANY, INC., OF NIAGARA FALLS, NEW YORK, A CORPORATION OF NEW YORK

CRACKER CADDY

Application filed February 16, 1925, Serial No. 9,417. Renewed April 26, 1929.

This invention relates to cracker caddies. It is the object of the present invention to afford a cracker caddy which can be made with less material than the prevailing type of 5 cracker caddy now on the market; which has a lid or cover which is permanently hinged to the body of the caddy, and which can be very much more satisfactorily sealed with one or two wire stitches, thereby making a very 10 much more secure sealing, and very much cheaper.

The now prevailing way of manufacturing these cracker caddies is to provide a separate cover, which is made as a sort of rectangular 15 lid having flaps on the four edges; in order to secure these flaps together at the four corners, two of the flaps have to be made double. This is the so-called Richardson caddy, patented September 21, 1920, and March 2, 1921. 20 These double flaps result in considerable lengthening of the blank, of which the cover is made. The cover is sealed on by means of a relatively broad sealing tape, which requires considerable sealing material, and 25 which is not nearly as strong as the form of sealing I am about to describe. The great waste in this form of container is that the body portion of the container is made of a single blank which has four overlapping flaps 30 at the bottom. These four overlapping flaps at the bottom take almost twice as much material to make the bottom of the case as is actually required. This will be more clearly brought out by comparison of the structure 35 35 I am about to describe.

Referring to the drawings:

Fig. 1 is a perspective view of the cracker caddy having the body of the case constructed along the line of what is now known to 40 the trade as the "Bliss No. 4 box".

Fig. 2 is a perspective of the same case, showing the lid in completed relation.

Fig. 3 shows the completed and sealed container.

Fig. 4 is a plan view of the main blank.

Fig. 5 is a plan view of one of the end blanks.

Fig. 6 is a section on the line 6—6 of Fig. 3. 50 Fig. 7 is a section on the line 7—7 of Fig. 3.

Fig. 8 is detail section showing how the final sealing stitch is taken.

Fig. 9 is a perspective of a sealed caddy of a modified form, embodying the so-called "No. 2 Bliss box" construction. 55

Fig. 10 is a plan view of the main blank.

Fig. 11 is a plan view of one end blank.

Fig. 12 is a plan view of the other end blank.

Fig. 13 is a perspective view of this form 60 of caddy before it is sealed.

Fig. 14 is a section taken on the line of 14—14 of Fig. 9.

Fig. 15 is a section on the line 15—15 of Fig. 9. 65

The caddy shown in the first modification is one which is built on the "Bliss No. 4 box" principle, that is, a flush end box of three blanks in which the corner flaps are on the major blank. The Bliss box of this general principle is shown in the Bliss Patent No. 1,375,127, issued April 19, 1921. The major blank comprises a strip of material scored and cut to form the side walls *a* and *b*, and the bottom wall *c* and lid *d*. These side and 70 bottom walls have corner flaps correspondingly lettered but use a "1" as exponent. The lid is provided with lid flaps *d*¹, *d*² and *d*³, the flaps *d*¹, and *d*² being provided with gusset-like wings *d*⁴ and *d*⁵. The two end blanks 75 are formed of the flat sheets *e*, preferably provided with the top flaps *e*¹. These two end blanks *e*—*e* are set in under the corner flaps *a*¹, *c*¹, *b*¹, as clearly shown in Figs. 1 and 2, and stitched thereto on a wire-stitching machine. This forms a box body identical with the box body shown in my prior 80 Patent No. 1,375,127, April 19, 1921, and known as the Bliss No. 4 box. It will be noted that the lid flaps *d*¹ and *d*² on the lid 85 line up with the corner flaps *a*¹, *c*¹ and *b*¹ on the other portions of the blank, so there is absolutely no waste whatever in cutting the blank.

Now referring to Fig. 2, it will be apparent how easy the lid is assembled together to form the usual flange or depth for the cover. The gusset-like wings *d*⁵ and *d*⁴ are folded over and secured to lid flap *d*³ by a single wire-stitch, as clearly shown in Fig. 2. 95 100

This forms a box cover which is hinged on the line g to the body of the case, and which has the usual box cover flange to give the cover depth. These flaps are made without requiring a double amount of material, and are so made that two of the flaps, viz: d^1 and d^2 are cut of material that would otherwise be waste in the blank. The other flap d^3 alone requires extra material for the blank.

It will be apparent that this form of caddy is very much more economical than a caddy in which the body is made of a single blank formed into a tube by one manufacturer's seam and with the bottom formed by two pairs of overlapping flaps giving the bottom substantial double material, which is largely a matter of waste.

A very important feature of this construction is that inasmuch as the lid is permanently fastened at one side or the back of the case, the whole case may be sealed by simply turning out the sealing or top flap h on one end of the blank and dropping down the cover over the same, as is clearly shown in Fig. 8. Also the side flaps d^1 and d^2 of the cover are slipped in behind a portion of the corner flaps a^1 , thereby pinching the rear corner of the side cover flaps between a part of these corner flaps and the end blanks e .

This is more clearly shown in Fig. 3 and in order to allow the side cover flaps to wedge behind the corner flaps, I omit the upper stitch in stitching the corner flap a to the end blank. In this way two of the side cover flaps are bound tight against the walls of the box and the remaining side flap d^3 of the cover is presented over the turned down sealing or top flap h . A blade anvil A may be inserted under these two flaps and the stitch i taken. In this way the cover is secured to the caddy box at all four sides. One side is the hinge, two sides are caught behind the cover flaps and the remaining side is stitched to the sealing flap h , and when this cover is stitched it is impossible to withdraw the side flaps d^1 and d^2 from out behind the cover flaps without breaking the sealing stitch. This eliminates the expensive process of shipping by pasting a big wide strip of sealing tape across the top of the case and part way down the sides. Furthermore, such a sealing strip very often interferes with advertising matter either on the top of the case or on the sides.

It will be noted from Figs. 1 and 2, that a line of perforations j may be placed across the lid for the purpose of giving a tear line for the grocer to tear off the lid when he opens up the case, as he very often does, and places a transparent cover over the box to prepare the contents for vending.

The modification in Figs. 9 to 15 inclusive, is one that is built along the lines of the "Bliss No. 2 box", which is shown clearly in my Patent No. 1,512,157, issued October 21.

1924. This involves the same principle in caddy construction with this exception, that conformable with the principle of the "Bliss No. 2 box", the corner flaps are on the end blanks which are here designated k and m . These corner flaps are designated m^1 , m^2 , m^3 and m^4 , and k^1 , k^2 and k^3 . In order to cause the lid flaps which are designated n^1 and n^2 to line up with the corner flaps in the blank structure, it is therefore necessary to couple up the lid blank n with one of the end blanks k , as clearly shown in Fig. 12. This is in order to make these two sets of flaps to line up in one blank and therefore not have any waste; hence the lid blank is lined up with one of the end blanks instead of the main body blank as is the case in Fig. 4. Compare Fig. 10, which is the major blank, and which contains only the bottom r and two side walls s and t and the top flaps s^1 and t^1 . The cover is made in the same way, having gusset-like wings v — v , which are folded over and stitched to the flap x and the sealing is done in the same way by stitching the flap x to the sealing flap m^4 by the single stitch i . The flaps n^1 and n^2 are slipped in behind the flaps k^1 and k^3 respectively, as shown in Figs. 13 and 14 in the same way as the other form of caddy.

What I claim is:

1. A caddy or box, comprising three blanks, some of which are provided with corner flaps and arranged to be fitted and assembled together by securing the corner flaps to the adjacent blanks to provide a flush-end case, one of the blanks being provided with a hinging lid portion having three lid flaps or flanges, and one of the blanks having a top flap, the said lid flaps being arranged to be secured together and the caddy sealed by engaging a part of two lid flaps behind a portion of two corner flaps and by turning the said top flap under the remaining lid flap and stitching the same together.

2. A cracker caddy or the like composed of fiber board comprising, a box body having four side walls and a bottom wall, an extension on the top of one of said side walls adapted to be turned downwardly outside the wall and substantially parallel therewith, a cover blank hingedly connected to one of the walls which is opposite the wall having the extension, said cover blank being of a size to completely close the top of the box body, a flange on the three free edges of the cover blank composed of three flaps secured together so that the flange is self-retaining adapted to lap over the corresponding three walls of the box body when the cover is in closed position with the flanged part on one edge of the cover lapping the said extension to hold the same confined thereby, and a stitch connecting the said flange part and the said extension to hold the cover in sealed and closed position, said stitch being

independent of and outside of the adjacent body wall whereby to permit of sealing and easily opening the caddy while the same is loaded.

- 5 3. A cracker caddy or the like composed of fiber board comprising three blanks which are stitched together to form a box body, two of said blanks forming end walls and the third blank being bent to form two side walls,
10 a bottom and a cover, said third blank having an extension which rises from the top edge of a wall formed by said third blank, which wall is opposite the wall next adjacent the cover, said extension being adapted to be turned down outside the wall, said third
15 blank also having extensions projecting from the three free edges of the cover which are turned to substantially at right angles and secured together at their meeting corners of
20 the cover to form a cover flange, said flange lapping the upper edges of said walls and on the outside thereof when the cover is closed with the flange part on one edge of the cover lapping the said first named extension to hold the same confined within the flange, and a stitch connecting this flange part and first mentioned extension to hold the cover in closed and sealed position whereby to permit of sealing and easily opening
25 of the caddy while the same is loaded.
30

In testimony whereof I have affixed my signature.

HERBERT R. BLISS.
